UNITED STATES PATENT OFFICE.

GEORGE ERDMAN, OF HUDSON, NEW YORK, ASSIGNOR TO GIFFORD-WOOD COMPANY, A CORPORATION OF NEW YORK.

CONVEYER.

1,269,588.

Specification of Letters Patent. Patented June 18, 1918.

Application filed May 5, 1914. Serial No. 836,431.

To all whom it may concern:

Be it known that I, GEORGE ERDMAN, a subject of the King of Prussia, residing at Hudson, county of Columbia, State of New

5 York, have invented certain new and useful Improvements in Conveyers, of which the following is a specification.

My invention relates to endless conveyers or elevators for transporting materials and 10 merchandise of various kinds, as, for example, milk cans, blocks of ice, or packages of various kinds, and more particularly to combined elevating and lowering conveyers for either raising or lowering articles from 15 one floor or level to another, and for picking up articles at one level and delivering them at another lever. My invention is adapted to any type of conveyer having carriers mounted on an endless belt or chain, and is 20 particularly applicable to vertical endless conveyers in which the carriers for the articles are pivotally connected to an endless belt or chain running over suitable wheels at the top and at the bottom of the conveyer. In machines of this type the carriers 25 must go around the top wheel in crossing from the upwardly moving side of the conveyer to the downwardly moving side, and must go around the bottom wheel to return 30 to the upwardly moving side. In many types of conveyers the carrier can swing about its point of suspension as it passes around the top or the bottom wheel and as a result the carrier may tip enough to cause 35 trouble.

The principal object of my invention is to simplify and improve conveying or elevating and lowering machines to the end that such machines may be operated rapidly, 40 safely, and to a large extent automatically. A further object of my invention is to provide an endless conveyer in which the carrier is mounted in an improved manner and is positively controlled at every point in its 45 travel, so that it cannot inadvertently tip or tilt, even when eccentrically loaded or when passing the top or the bottom wheel. Another object is to improve the method of connecting the carriers of conveyers to the 50 endless chain. A still further object is to improve the means for loading the articles on the carriers and for automatically dis-

charging the articles at desired points. Another object is to make general improvements in endless conveyers of this character, as hereinafter pointed out.

In carrying out my invention I prefer to pivotally connect the carrier to an endless element, such as a belt or chain, and to provide suitable means for positively and definitely steadyng and holding the carrier in proper position at all points in its travel. In the preferred construction I provide a flexible endless controlling member, such as a chain, flexible cable, or similar controlling means, which is always connected to the carrier and travels at such a rate and maintains such a relation to the chain or belt on which the carrier is mounted that the carrier is positively steadied and held by it in proper position. The flexible control member or chain may be connected to and control the carriers in any suitable way. I may, for example, provide the carrier with a projection or arm which is so connected to the control chain as to give the chain positive control of the carrier throughout its travel. I prefer to pivotally mount the carrier on the endless element or elevator chain in such a manner that the weight of the loaded carrier does not tend to bend the chain sidewise out of its plane of movement and thereby cause undue binding and friction. In the preferred construction the carrier is mounted between two elevator chains upon a rigid member, such as a shaft, which is journaled on the two chains. The carrier is usually mounted above the shaft to pick up the load before the shaft passes through the loading station, so that the article receiving surface of the carrier is either substantially in line with or preferably above the shaft, instead of being very considerably below the point of suspension, as is usually the case. At each different floor or level I provide 90 stations which when set in one position will cause articles placed on the station to move automatically into position to be picked up by the carriers, and when set in another position will automatically take the articles off the carriers and deliver them at the desired place. These stations may be rendered inoperative when desired, and are preferably constructed to fold back out of the way.

Usually the force of gravity will move the article off the carrier at the delivery station, but in some cases I provide automatic means for positively removing the articles from the carrier as it passes a station set to deliver articles from the carrier.

My invention will best be understood in connection with the accompanying drawings in which, merely for purposes of illustration, I have shown some of the various forms in which my invention may be embodied and in which Figure 1 is a longitudinal vertical section of a form of machine embodying my invention and particularly adapted for raising and lowering articles such as milk cans; Fig. 2 is a plan view of the carrier for the milk cans; Fig. 3 is a side view of this carrier; Fig. 4 is a side view of a special form of link in which the carrier is journaled; Fig. 5 is a plan view of a station at which the milk cans may be loaded onto the conveyer or automatically discharged from it, depending upon how the station is set; Fig. 6 is a side view of this station; Fig. 7 is a side view of this station folded back out of the way; Fig. 8 is a view of an automatic discharging station which automatically and positively forces the milk can off the carrier; Fig. 9 is a transverse section along the line 9-9 of Fig. 10; Fig. 10 is a plan view of the top or driving end of an elevating and lowering conveyer especially suitable for ice; and Fig. 11 is a longitudinal vertical section of this conveyer, along the line 11-11 of Fig. 9, and also showing a similar section of the bottom end of the conveyer.

In the particular form of conveyer shown in Fig. 1 a vertical framework 1 made of any suitable material, preferably steel or iron, extends through the various floors or levels at which the articles are to be loaded on the conveyer and unloaded from it. The moving parts of the conveyer are mounted on this framework. In the particular type of conveyer shown the endless flexible element comprises two endless conveyer or elevator chains 2 which run side by side at the same speed. Each conveyer chain runs upon a driving or conveyer sprocket 3 near the top, and an idler wheel or sprocket 4 near the bottom of the framework 1. The two driving sprockets 3 are keyed to a strong driving shaft 5. The driving sprockets may be mounted at the bottom and the idlers at the top if considered preferable. Carriers 6 are mounted between the conveyer chains 2 and by suitable means, such as hereinafter described, the articles are loaded upon and discharged from the carriers at the desired levels. The conveyer may be driven from any suitable source of power connected to the driving sprockets 3.

Each carrier 6 is pivotally mounted on the endless flexible element, such as the

chains 2, in order that it can be kept horizontal when passing the head wheels or the bottom wheels. The carrier, as best shown in Fig. 2, is provided with a number of fingers or projections 7 which constitute a platform for the load. In the preferred construction the carrier is pivotally mounted on the chains by means of a rigid member or shaft 8, which extends through the carrier very close to the surface on which the load rests and is journaled on the chains 2. When the carriers are between the top and bottom wheels they are compelled to move in a definite path by guides 9, which in the particular conveyer shown are vertical and co-operate with the shaft 8.

The carriers 6 would be apt to tilt or swing about their pivots 8 and spill their loads, especially when passing the head wheels or the bottom wheels, unless steadied or controlled in some way. In accordance with my invention I prevent tilting of the carrier and positively control its position by an improved control mechanism by means of which the carriers are positively controlled and steadied at every instant and at all points in their travel, especially when passing both the top and the bottom wheels of the machine. In the preferred construction each carrier has a controlling projection or arm, such as a control arm 10, rigidly connected to it, as, for example, by being keyed to the shaft 8. The particular form of control mechanism which I prefer comprises a control member, such as an endless flexible guide or chain 11, mounted near the endless element or conveyer chain 2 and driven in such a manner that a point or link of the control member travels in a path parallel to and identical in length and shape with the path of movement of the pivot of the carrier. This point or link of the control member is permanently connected to the carrier in some suitable way, as, for example, through the control arm 10, and thereby the carrier is steadied at every instant and at every point in its travel.

The endless flexible control member or chain 11 may be mounted in various ways to travel in the desired path identical in length and shape with the path of the conveyer chains 2. I prefer to mount the control chain 11 on a driving sprocket 12 at the head of the conveyer and on an idler sprocket 13 at the bottom. These control sprockets, corresponding in size to the conveyer driving sprockets 3 and the conveyer idler sprockets 4 are mounted to one side of the plane of the conveyer sprockets, and preferably above them, although the control sprockets can be mounted in any position as long as the two sprockets 12 and 13 are equally eccentric to the elevator sprockets 3 and 4 and are the same distance apart as the elevator sprockets. The endless con-

trol member or chain 11 is driven in synchronism with the conveyer chains in any suitable manner, as, for example, by gearing which compels the conveyer sprocket 3 and the control sprocket 12 to rotate at the same rate and to maintain always the same relation to each other. One way in which this result may be accomplished is shown in the drawing, in which a gear wheel 14 on the shaft of the conveyer driving sprocket 8 is connected through an intermediate gear 15 to a similar gear 16 rigidly connected to the control chain sprocket 12. The entire machine may be driven by some suitable motor 17 connected through suitable gearing to the sprockets at the upper or driving end of the machine.

The control chain 11 may be connected to the control arm 10 of the carrier in various ways, as, for example, by a pin 18 secured to the control arm and pivotally connected to the chain 11 by a slot 19. This control arm may also be provided with a roller 20, which travels in fixed vertical guides 21 mounted on the frame 1 and parallel to the guides 9. This roller 20 may, if desired, be mounted on the pin 18. When the carrier is between the top and bottom wheels, it is steadied by the fixed guides 9 and by the fixed guides 21, as well as by the control chain 11. The carrier is necessarily out of the fixed guides, when passing either the top or bottom wheels of the conveyer, but the control chain 11 positively controls and steadies it at every instant throughout its whole travel, so that there is no shock, jar, or even slight tilting of the carrier when it leaves or enters the fixed guides, and it is positively steadied and held horizontal while passing both the top and bottom wheels. The carrier is under as positive control when out of the vertical guides as when in them, and the permanent connection of the control chain to the carriers eliminates any possibility of trouble, due to tipping or swinging of the carriers at any point in their travel, to the control arm striking the ends of the vertical guides or to the control arm or shaft 8 failing to enter the guides smoothly.

By using a rigid member or shaft 8 journaled on both conveyer chains 2, I eliminate the strains and friction between links which result when the load on the carrier is to one side of the plane of the chain and therefore tends to tilt side wise the link in which the carrier is journaled. The same tendency to bend the chain sidewise and increase the friction between links is present when the carrier is suspended from the chain by comparatively long arms, as the arms yield slightly under load and permit the links to which they are pivoted to tilt sidewise. Since the shaft 8 would displace the load if it passed through a loaded station be-

fore the carrier, I mount the carrier on the shaft 8 in such a position that the carrier picks up the load before the shaft 8 reaches it, so that in an elevator, for example, the carrier is mounted on the upper side of the shaft, as shown in Fig. 3. As a result of this construction the center of gravity of the loaded carrier is above the pivot or shaft 8, but the control mechanism prevents tilting or tipping of the carrier, which is held horizontal at all points in its travel.

Various forms of carriers may be used, depending upon the particular article which is to be handled. For milk cans and similar articles I prefer to construct the carrier, as shown in Fig. 2, with fingers or arms which hold the milk can, and these may be provided with a lip on the outer end to hold the can in place, or may be roughened to prevent slipping of the can.

The shaft 8 of the carrier is journaled on the conveyer chains 2 in any suitable way, but I prefer to use a special link 22, best shown in Fig. 4, and having a bearing 23 in which the shaft 8 is journaled. This bearing is preferably to one side of the longitudinal axis of the chain, and has the advantage that the only effect of a heavy load on the carrier is to tilt the link 22 slightly in the plane of the chain, which does not increase the friction between links. This particular form of link need not necessarily be used, but is advantageous, as the bearings for the carrier shaft 8 can be made as large as desired, yet the chain with the special links in it will run on sprocket wheels of the usual type. I prefer to use a similar link for the pin 18, with the modification that the opening 19 in the link is elongated to allow for slight stretching of the control chain 11.

To facilitate loading and unloading I provide stations by means of which the milk cans, packages, or other articles can be delivered to the carriers of the conveyers or can be automatically discharged from the carriers at the will of the operator. Each station is so constructed, as best shown in Fig. 5, that the arms of the carrier 6 will pass through the station, but the article upon the carrier will not. The station is preferably constructed, as shown in plan in Fig. 5, with a pivoted rectangular frame made of end pieces 24 which are connected by journals 25 to a side shaft 26, and also by journals 27 to a pivot shaft 28 which in turn is mounted in journals 29 on the frame work of the machine. The whole frame is swung up or down at will, as shown in Figs. 1 and 6, by some suitable means, such as a hand lever 30 connected by links 31 to the side shaft 26. When in one position, as shown in full lines in Fig. 1, articles placed upon the station will move away from the pivot and into position to be picked up by the carrier 6, so that it acts as a receiving or loading

station. When in dotted line position it acts as a discharging station for unloading the carriers which move down through the station. The station is preferably provided with fingers 32 rigidly mounted on the shafts 26 and 28 in a position to support the article and at the same time permit the carrier to pass through between them. These fingers may be provided with some anti friction device such as rollers 33 which are preferably mounted upon ball bearings. Where articles such as milk cans are to be handled I prefer to provide each receiving station with some suitable centering device such as a stop 34 for stopping and centering the cans on the station. This stop is preferably pivoted to the station in such a way that it can be swung up out of the way, as shown in dotted lines in Fig. 6, when large articles are to be loaded on the station, or when the station is set to act as a discharge station.

When cans or similar articles are to be loaded on the conveyer, the bottom station of Fig. 1, for example, is inclined, as shown in full lines, so that the articles placed upon it will move away from the pivot of the station into position between the conveyer chains 2 and in alinement with the carrier. As the carrier passes up through the station the article is picked up. When the conveyer runs in the opposite direction, and articles are to be automatically discharged at this same station, it is set as shown in dotted lines, and the articles are left upon it as the carrier passes down through it.

In order that any station may be rendered inoperative whenever desired I provide means for swinging the fingers 32 back out of the way at the will of the operator. This may be done in various ways, but the preferred construction is that best shown in Fig. 6, in which the station is in position to operate, and in Fig. 7, which shows the station when it is inoperative. The shafts on which the fingers 32 are fixed are provided with cranks 35, one of which may have a handle for moving it. The cranks are connected by a link 36 in such a manner that movement of the handle will throw both sets of fingers back out of the way from the operative position shown in Fig. 6 into the inoperative position shown in Fig. 7. Movement of the handle in the other direction will return both sets of fingers into operative position. A further advantage of this construction is that in case the station is set as shown in Fig. 6 when it should be set as shown in Fig. 7, and a loaded carrier passes through the station from below, no damage is done, as the load on the carrier merely lifts up the fingers 32 and swings them back out of the way. If the fingers were rigid the load would be crushed or the station broken.

In some cases it may be desirable to pro-

vide means for automatically forcing the article off the fingers of the delivering station instead of depending upon the force of gravity. In accordance with my invention I accomplish this result by an automatic mechanism, as shown in Fig. 8, in which a discharge member 37 is pivotally mounted on the rectangular frame of the station. This member has a projecting arm 38 which is normally held by a counterweight 39 in the position shown in dotted lines, where it will be engaged and moved by the carrier which descends through the delivery station, and leaves the milk can or other article upon the rollers 33. The movement of the carrier swings the discharge member 37 into the position shown in full lines, whereby the milk can or other article is pushed off the delivery station and out of the way of the following carrier. As the carrier moves on the counterweight returns the arm to normal position. I prefer to construct the arm 38 in such a manner that it is rigid when the carrier pushes it down, but yields when an ascending carrier engages it. To accomplish this result I may pivot the arm at 38' and provide it with a projection 40 which prevents the outer end of arm 38 moving downward, but permits it to move upward.

When my invention is embodied in a conveyer for blocks of ice and similar articles, I prefer to modify the construction slightly, as shown in Figs. 9, 10 and 11. In this form of the machine I provide at the upper or driving end two conveyer sprockets 41 mounted with their shafts in alinement and with sufficient space between them to permit the passage of the block of ice. By suitable means the two sprockets are maintained in definite relation to each other, as though they were keyed to the same shaft. In the preferred arrangement each sprocket 41 is rigidly connected to a gear wheel 42 and these two gear wheels are kept in proper relation by meshing with two gears 43 mounted on a cross shaft 44, which extends across the upper end of the machine in a position where it will be out of the path of the blocks of ice. The control chain driving sprocket 45 is mounted above and slightly to one side of the conveyer driving sprockets 41, and is driven through gearing 46 or other suitable connections so as to run at the same speed as and in definite relation to the conveyer sprockets 41. The entire mechanism may be driven from some suitable source of power connected to the sprockets 41, as, for example, through gearing and countershafts to the cross shaft 44.

In order to transfer the blocks of ice from the ascending side of the conveyer to the descending side in a minimum space and with the simplest and most efficient machinery, the block of ice should be shifted horizon-

tally as soon as it reaches the upper end of the conveyer, whereby unnecessary lifting is avoided and less head-room is required. To this end I provide, as best shown in Fig. 10, 5 idler wheels or sprockets 47, for the conveyer chains, mounted and spaced apart like the conveyer driving sprockets, but not geared together, and an idler wheel sprocket 48 for endless flexible guide or control 10 chain 11.

The blocks of ice are usually rectangular in shape and are best carried on edge. I therefore provide a special form of carrier comprising sides 49 spaced apart and of 15 suitable size for the cakes of ice, and provided with sharp points to prevent the ice slipping off. The carrier is rigidly mounted on a transverse shaft, or pivot 50, which is journaled in suitable bearing blocks on the 20 elevator chains. Preferably these bearing blocks are constructed like the blocks 22 shown in Fig. 4. To steady and control the carriers I provide each one with a control arm 51 rigidly secured to the end of the 25 shaft 50. The other end of the control arm is permanently connected to the endless guide or control chain 11. I prefer to make the connections to the control chain by 30 means of a pin 52 firmly mounted in the control arm and projecting through an elongated slot in the link of the control chain. This pin 52 may have a roller 53, which travels in the fixed vertical guides 21.

The receiving and delivering stations for 35 the machine for handling blocks of ice may be constructed in the usual manner, or if desired, in substantially the same manner as the stations for the machine shown in Fig. 1, but modified in dimensions to adapt them 40 to coöperate with the carriers for the cakes of ice.

When the machine is in operation a cake of ice is placed upon the receiving station and slides down into proper position. An 45 upwardly moving carrier, passing up between the fingers of the receiving station picks up the block of ice. Tipping or tilting of the carrier during its upward movement is prevented by the fixed vertical 50 guides 9 and 21, and also by the guide or control chain 11. The carrier rises to the top of the machine and thereby lifts the cake of ice up between the idler sprockets 47. As 55 the carrier goes over the idler sprockets it begins to move in a horizontal direction toward the elevator sprockets. During this horizontal movement of the carrier the weight is supported in some suitable manner, preferably by rails or sills 58 mounted immediately beneath the horizontal portions of 60 the conveyer chains. In this particular arrangement the bearing links 22 of the carrier slide on the rails during the horizontal movement of the carrier. During its travel 65 around the sprockets and from one set of

sprockets to the other the carrier is entirely outside of the fixed guides, but it is positively controlled both at the top and bottom of the machine and at all times by the endless guide or control chain 11, to which 70 it is permanently connected. This chain runs in such a relation to the elevator chains that the carrier is positively and firmly held horizontal at all times and consequently the block of ice will not slide off. It is apparent that the horizontal part of the path of the carrier may be as long as desired, hence my invention is of great utility in horizontal as well as vertical and inclined conveyers. As the carrier goes around the conveying 80 driving sprockets and begins its descent, the shaft 50 enters the vertical guides 9, and the roller 53 enters the vertical guides 21. The carrier with the block of ice upon it descends and eventually reaches the delivery station, 85 where it passes through suitably arranged fingers so spaced as to permit the passage of the carrier but to engage the block of ice, which then slides off the delivering station either by the force of gravity or the action 90 of an automatic discharge device such as that shown in Fig. 8.

At the bottom of the elevating and lowering machine I provide idler wheels 55 for the elevator chains and control chain idler 95 wheels 54, arranged as best shown in Fig. 11, so that the descending carriers make a quick right angle turn around the idler wheels 54 and move horizontally across to the ascending side of the conveyer. During 100 all this horizontal movement they are outside the vertical fixed guides, but are firmly and positively controlled and held horizontal at every instant by the control chain. It is therefore possible to build the machine with very slight clearance between 105 the carriers and the bottom of the pit in which the conveyer is mounted. Since the idlers 54 and 55 may be small, comparatively little room below the lowest station 110 is required for transferring the carriers from the descending side to the ascending side, and consequently the bottom pit can be much shallower than with conveyers of the usual type. This not only cheapens and 115 improves the machine, but the carriers sweep out and clear the shallow pit of pieces of ice and rubbish that would otherwise accumulate and clog the machine. Carriers 120 which swing freely during their travel around the lower wheels cannot do this, and the pit must be much deeper to prevent damage due to swinging of the carriers.

A conveyer embodying my invention can 125 be run in either direction so that articles of any kind can be picked up on either side at any level and discharged on the other side at any level. If, through oversight, any of the stations are improperly set no damage results. Either the load will be discharged 130

at the wrong level, as the carrier descends, or else the fingers of the station will be lifted back automatically as the loaded carrier passes up through the station.

5 My invention is not limited to conveyers of the double chain type. It is furthermore not limited to vertical conveyers, as it is equally applicable to conveyers in which the greater part of the path of the carriers is horizontal or inclined, or both, as the endless guide or control chain will hold the carriers horizontal at every point in their path regardless of the length or shape of that path, since the control chain travels in a path exactly similar. I therefore do not wish to be restricted to the precise form shown and described, but intend to cover all changes and modifications within the scope of my claims.

20 What I claim as new and desire to secure by Letters Patent of the United States is:

1. In a conveyer, the combination of two endless flexible chains, a carrier pivotally mounted thereon, a third chain permanently connected to said carrier and mounted to move in a path parallel to and of the same length and shape as the path of the pivot of said carrier, and means for moving said third chain at the same speed as said two chains to maintain said carrier at substantially the same angle to the horizontal at every point in its travel.

2. In a conveyer, the combination with two chains, a carrier pivotally mounted on said chains, a control arm rigidly connected to said carrier, an endless third chain connected to said control arm and mounted to move in a path parallel to and a duplicate of the path of the pivot of said carrier, and means for driving said endless third chain in synchronism with said endless chain to positively maintain said carrier at a definite angle at every point in the travel of said endless chain.

45 3. In a conveyer, the combination of two endless flexible elements, a plurality of carriers spaced along said elements, each carrier being pivotally mounted on said two flexible elements to be supported entirely by said elements and having a projecting control member eccentric to the pivot of the carriers, and an endless flexible traveling guide connected to the control arms of said carriers at every point in the travel of said carriers and mounted to move in a path parallel to and a duplicate of the path of said flexible elements and in synchronism with said flexible elements to positively steady each carrier at every point in its travel.

60 4. In a conveyer, the combination of two endless flexible elements in the form of two loops, turning wheels at the ends of each loop, a carrier pivotally mounted on said elements, endless flexible traveling guide mounted to form a loop which is a duplicate

of and parallel to the loops formed by said endless elements, said traveling guide being permanently connected to said carrier to positively steady it during its movement around said turning wheels, and means for 70 causing said flexible elements and said traveling guide to travel in synchronism.

5. In a conveyer, the combination of two endless flexible elements, turning wheels for supporting said elements, carriers pivotally 75 mounted on and between said elements, an endless flexible traveling guide mounted beside said endless elements, to move at the same speed as said endless elements and in a path parallel to and a duplicate of the 80 path of said elements, and means for permanently connecting said carriers to said endless traveling guide to positively steady and control said carriers at every point in its movement.

85 6. In a conveyer, the combination of two endless flexible elements, mounted side by side, carriers pivotally mounted on and between said elements, a control arm rigidly connected to the pivot of each carrier and to one side of said elements, and an endless flexible traveling guide connected to said control arm and mounted to maintain a uniform distance and relation to the pivot of said carrier throughout its entire movement 95 on said endless elements and thereby positively steady and control said carrier at every point in its movement.

7. In a conveyer, the combination of an 100 endless element comprising two parallel conveyer chains, turning wheels for supporting the bends of said chains, a carrier mounted between said chains on a pivot journaled in said chains and projecting beyond one of said chains, a control arm rigidly connected 105 to the projecting end of said pivot, control wheels mounted to one side of said conveyer wheels with their axes equally eccentric to but parallel with the axes of said conveyer wheels, an endless control chain mounted 110 on said control wheels and permanently connected to said control arm to positively steady and control said carrier at every point in its movement, and means for driving said control chain in definite relation to 115 said conveyer chains.

8. In a conveyer, the combination of two parallel conveyer chains, a rigid bar extending from one chain to the other and journaled on said chains, a load carrier mounted 120 on said bar in position to engage the load before said bar reaches the load, and a third chain mounted to move parallel to said two chains and connected to said carrier for steadyng said carrier to prevent it tilting 125 about said bar as a pivot.

9. In a conveyer, the combination of two parallel endless flexible elements each in the form of a loop, a rigid cross bar extending from one element to the other and journaled 130

on said elements with one end projecting beyond one of the journals, a load carrying platform mounted on said bar with its load engaging surfaces above the bar, a control arm mounted on the projecting end of said bar, and a traveling guide in the form of a loop parallel to said elements and permanently connected to said control arm to

hold said platform horizontal throughout the travel of said platform. 10

In witness whereof, I have hereunto set my hand this 4th day of May, 1914.

GEORGE ERDMAN.
